UNITED STATES PATENT OFFICE.

THOMSON M. STONE, OF NEWARK, NEW JERSEY, ASSIGNOR TO JOHN L. ARMITAGE, OF SAME PLACE.

DESIGN FOR SHEET METAL.

SPECIFICATION forming part of Design No. 22,567, dated June 27, 1893.

Application filed April 21, 1893. Serial No. 471,348. Term of patent 3½ years.

To all whom it may concern:

Be it known that I, THOMSON M. STONE, a citizen of the United States, and a resident of Newark, in the county of Essex and State of New Jersey, have invented and produced a new and original Design for Decorative Sheet Metal, of which the following is a specification.

My invention consists in a design for decorative sheet metal,—the nature of which design is hereinafter pointed out with reference to the accompanying drawings, in which—

Figure 1 represents a face view of a piece of sheet metal ornamented with my design. Fig. 2 is a cross-section thereof in the plane x , Fig. 1.

The design is composed of conventionalized natural objects; its essential features consisting in continuous entwining branches, whose stems bear leaves of different size and character; fruits or berries in bunches arranged at the ends of short stems extending from the entwining branches, and scrolls or blossoms distributed on the entwining branches between the several leaves. Additional bunches

of fruits or berries may be distributed at the ends of the leaves. The conventionalized natural objects are placed in relief on a contrasting back-ground possessing the nature of a "pin" ground.

The specific arrangement of the several natural objects and their relation to each other can be sufficiently understood from the drawings to enable others skilled in the art to make and use my invention without further verbal description thereof.

What I claim as new, and desire to secure by Letters Patent, is—

The design for decorative sheet metal embracing the entwining branches with stems, leaves and fruits or berries, all arranged substantially as shown and described.

Signed at Newark, in the county of Essex and State of New Jersey, this 19th day of April, A. D. 1893.

THOMSON M. STONE.
